A. H. Evans & Co.

UNITED STATES PATENT OFFICE.

ALFRED B. WROTH, OF OMAHA, NEBRASKA, ASSIGNOR TO CHRISTIAN DIETRICH, OF SAME PLACE.

ICE-CHEST FOR BEER.

SPECIFICATION forming part of Letters Patent No. 314,984, dated March 31, 1885.

Application filed July 15, 1884. (No model.)

To all whom it may concern:

Be it known that I, ALFRED B. WROTH, a citizen of the United States, residing at Omaha, in the county of Douglas and State of Nebraska, have invented certain new and useful 5 Improvements in Ice-Chests for Beer, of which the following is a full, clear, and exact description, reference being had to the accompanying drawings, forming part of this specification, in which—

Figure 1 is a vertical section of an ice-chest with my improvements attached. Fig. 2 is a cross-sectional view on the line $\alpha\alpha$ of Fig. 1.

My invention relates to an improvement in 15 chests adapted to hold barrels, kegs, or other vessels containing liquids—such as beer—or any other material in such a manner that a packing of ice is brought in close proximity to the outside of the said vessels; and my invention consists in the novel arrangement and 20 combination of devices hereinafter set forth and claimed.

To enable others skilled in the art to make and use my invention, I will now proceed to 25 describe the exact manner in which I have carried it out.

In the said drawings, A represents an ice-chest of any desired form and size; but I prefer to use one like that shown in the drawings, 30 which is rectangular in cross-section and provided with a closed top and bottom, as shown at a and b .

At the point c , within the chest A, is a projecting ledge, B, which is firmly secured to or 35 may be made to form a part of the sides of the chest, for a purpose hereinafter explained.

Within the bottom b is formed a socket for 40 the reception of the tapered end of a central vertical shaft, C, which extends upward, and has its upper end passed through a plate, E, which is also firmly secured to the sides of the chest. This plate is perforated with a series of radial perforations through which the cold water passes, and thence down upon the 45 barrel or kegs into the lower compartment, from which it can be drawn off by any well-known means, thereby keeping the contents of said barrel or keg always cool and ready for use.

Upon the vertical shaft C is formed a hub 50 provided with arms D, extending outward, and upon the outer ends of each of these arms is suitably secured a small roller or caster, which rests upon the projecting ledge B in such a manner that the shaft and arms upon 55 which the vessels rest can be easily and speedily revolved, so that when the barrel or keg upon one of the arms is emptied of its contents the said barrel can be moved out of the way, when another vessel is brought up on 60 line with the opening formed in the side of the chest. The opening just referred to may be closed by the hinged doors, as shown, thereby making an air-tight compartment. It will be noticed that between the arms D and 65 the inner sides of the chest is left a space the purpose of which is to allow the faucet attached to the keg to pass. Thus it will be seen that the entire surface of the keg, as well as the faucet, is confined within the chest. 70

To more thoroughly illustrate my invention, I have shown the arms D connected together by cross-bars d , each of which is formed with a curved surface corresponding to the form of the keg or barrel and upon which the 75 keg rests.

The space between the perforated plate E and the top a of the chest is for the reception of ice, and in the side or top of the chest may be formed a door, through which the ice is 80 admitted.

From the foregoing description it will be seen that the device is adapted to be used in hotels, saloons, or private families for various purposes; but I prefer using it as a chest for 85 beer, and from its construction it will be seen that it can be placed in position near the operator, who, when one keg becomes empty, pushes the said keg out of the way, when another keg is brought in place, and this operation is repeated until all the kegs are emptied 90 of their contents, when they can be removed through the door before referred to.

Having thus fully described my invention, what I claim as new, and desire to secure by 95 Letters Patent, is—

1. In combination with an ice-chest having a projecting ledge, and an ice-chamber formed

by the frame of the chest, and a perforated plate, E, the vertically-revolving shaft having a hub provided with inclined arms D and cross-bars *d*, with curved surfaces, the said arms adapted to receive and hold a keg or barrel, substantially as and for the purpose set forth.

2. The combination, with an ice-chest constructed substantially as shown and described, of a revolving vertical shaft having a hub provided with inclined projecting arms D and cross-bars *d*, each of said arms being provided with a roller or caster adapted to engage the

projecting ledge B, substantially as and for the purpose herein specified.

3. The herein-described ice-chest A, provided with doors, as shown, the perforated plate E, projecting ledge B, vertically-revolving shaft C, having a hub, and projecting arms D, cross-bars *d*, and rollers or casters secured to said arms, all arranged to operate substantially as herein set forth.

ALFRED B. WROTH.
